CYLINDER COCK

Robert H. George, Philadelphia, Pa., assignor to
 George Manufacturing Company, Inc., Philadelphia, Pa., a corporation of Delaware

Application March 9, 1933, Serial No. 660,083

8 Claims. (Cl. 121—134)

My invention relates to cylinder cocks, that is to say, to devices adapted to be mounted on the cylinders of engines, particularly of locomotives, for the purpose of removing the condensation 5 water therefrom.

My invention relates particularly to that type of cylinder cock in which the valve is normally held on its seat by fluid pressure under the control of the operator, and which opens automatically whenever undue pressure occurs in the engine cylinder by reason of high compression or the accumulation of condensation water therein.

Heretofore, in the use of automatic cylinder cocks of the type above mentioned, certain difficulties have been experienced which have hindered their universal adoption, notwithstanding it is recognized that cylinder cocks of this type have certain inherent advantages.

For example, it is well known that the condensation water passing through the cock contains a considerable quantity of broken down lubricating oil, and in some instances grit, which passes down along the valve stem into the piston chamber, fouling the same and eventually resulting 25 in the destruction of the working parts.

Also the water which passes down along the valve stem collects in the piston chamber, freezing in cold weather and rendering the valve inoperative.

Also, in most of the automatic cylinder cocks at present in use, there is considerable leakage past the piston of the air used for the control of the valve.

Also in the use of cylinder cocks of this type, it is sometimes necessary to make an emergency adjustment for the purpose of holding the valve on its seat, particularly in the event of failure of the air supply to the operating cylinder of the valve. The most common form of device used for this purpose comprises a bolt threaded in the bonnet of the valve, but this form of locking means is objectionable in that considerable leakage of air often takes place where the bolt is threaded in the bonnet.

The principal object, therefore, of my present invention is to provide, in an automatic cylinder cock, means for preventing the condensation water, and the oil and grit carried thereby, from passing downwardly into the operating cylinder of the valve.

A further object of my invention is to provide an improved form of operating piston for such cylinder cocks.

55 A further object of my invention is to provide

improved means for holding the valve in the closed position should occasion require.

A further object of my invention is to provide a cock of the character aforesaid, which will be simple, efficient, and inexpensive in construction.

A further object of my invention is to provide a cylinder cock of the character aforesaid, in which the various parts are so co-ordinated that the details of construction may be greatly improved.

The nature and characteristic features of my invention will be more readily understood from the following description, taken in connection with the accompanying drawing forming part hereof, in which:

Figure 1 is a vertical, central section of an automatic cylinder cock embodying the main features of my present invention;

Fig. 2 is a vertical section thereof, taken transversely to Fig. 1, certain of the interior parts being shown in elevation;

Fig. 3 is an underneath plan view thereof; and

Fig. 4 is a view similar to Fig. 1, but with the parts in the positions assumed when the valve is locked in the closed position.

It will, of course, be understood that the description and drawing herein contained are illustrative merely, and that various changes and modifications may be made in the structure disclosed without departing from the spirit of the invention.

Referring to the drawing, there is there shown a preferred embodiment of my invention. As illustrated, 5 is a cylindrical casing provided with a treaded nipple 6 at the upper end thereof for mounting the same in the wall of the engine cylinder. The nipple 6 is provided with a port 7, at the lower end of which there is mounted a ring member 8, having a valve seat 9. The ring member 8 is preferably threaded into the interior of the casing 5 at the lower end of the port 7, so that the same may be made of a different metal, and be replaceable if desired. The central opening in the ring member 8 forms a continuation of the port 7 in the nipple 6.

The side wall of the casing 5 is provided with an opening 10 forming a communication between the valve chamber 11 and the exterior of said casing, to permit the water which passes through the port 7, when the valve is open, to be drained away.

The valve member 12 is mounted in the chamber 11, being vertically movable therein and having one face 13 complementary to the seat 9 provided by the ring member 8. The valve 12 has

- a downwardly extending stem 14 which extends through and is guided in a central aperture in a guide member 15. The guide member 15 is mounted in the interior 5 of the casing 5 at the bottom of the valve chamber 11, being threaded therein in a manner similar to that of the valve seat ring 8. The guide member 15 forms a horizontal partition separating the valve chamber 11 from the piston chamber 16 in the lower portion of the casing 5.
- The guide member 15 is provided with an upwardly extending annulus 17, which projects into a complementary recess 18 in the under side of the valve member 12. The upwardly projecting annulus 17 provides a guard which prevents the water, and any contaminating material contained therein, from passing downwardly along the surface of the valve stem 14 into the chamber 16 below the guide member 15.
- The lower end of the valve stem 14 is reduced in diameter, as at 19, and upon this reduced portion there is mounted a disk 20, forming one of the elements of the piston structure. A gasket 21 is interposed between the disk 20 and the shoulder provided at the point where the valve stem 14 is reduced in diameter, this gasket being of any suitable packing material to prevent leakage at this point.
- A piston packing is mounted on the under face 30 of the disk 20, and comprises a flat circular portion 22 having a downwardly projecting peripheral rim 23 which bears against the inner surface of a sleeve 24 mounted in the lower end of the piston chamber 16 of the valve casing 5.
- A spreader ring 25 of spring wire is mounted on the inner side of the rim portion 23 of the piston packing member, and insures the bearing of the working surface of said packing member against the inner surface of the sleeve 24.
- The piston packing member and the spreader ring are held in place by a disk 26 mounted on the reduced portion 19 of the valve stem 14, the periphery of said disk 26 being recessed as at 27 to receive the spreader ring 25. The lower end 40 of the reduced portion 19 of the valve stem 14 is threaded, and a nut 28 is mounted thereon to hold all of the parts of the piston structure assembled on said reduced portion of the valve stem.
- A coil spring 29 is mounted in the piston chamber 16 of the valve casing 5, bearing at the lower end against the top surface of the disk 20, and at the upper end against the under surface of the guide member 15. On each side of the lower end of the casing 5 there is provided a boss 30, having a threaded recess 31 into which the end of an air pipe 32 may be threaded. It should of course be understood that the air pipe 32 will be connected to one side only of the casing 5, and the recess 31 provided at the other side thereof 50 may be closed by means of a pipe plug 33, this arrangement being provided so that the cylinder cock may be used either right or left hand as required.
- A port 34 extends from the inner end of each of the recesses 31, through the casing 5 and through the sleeve 24, to a point below the lowermost position of the packing member of the piston structure.
- The lower end of the casing 5 is closed by a bonnet member 36, which is secured to the casing by means of bolts 37. The central portion of the bonnet member 36 is provided on one side with a recess 38, which is normally disposed inwardly to provide a clearance for the lower end 60 of the valve stem 14. The other side of the bonnet 36 is provided with a projecting boss 39, normally disposed on the outside, as shown in Fig. 1 of the drawing, but adapted, when said bonnet 36 is reversed, to bear against the lower end of the valve stem 14, and thereby when the bolts 37 are properly tightened, to hold the valve member on its seat, as shown in Fig. 4 of the drawing.
- A gasket 40 is interposed between the upper surface of the bonnet 36 and the under surface 10 of the casing 5, to prevent leakage at this point.
- The operation of the device will be readily apparent. The coil spring 29 tends to impel the piston, and consequently the valve, downwardly, thereby opening the valve whenever there is no 15 air under pressure below the piston, so that when the valve is in this position any condensation water which has accumulated within the engine cylinder will be permitted to drain through the port 7 of the valve chamber 11, and thence out 20 through the opening 10.
- When the engine is operating normally, air under pressure will be fed through the pipe line 32 to the recess 31, thence through the port 34 to the space below the piston, forcing the piston 25 upwardly and causing the valve to be seated, thus closing the port 7 which communicates with the engine cylinder.
- It will be noted, however, that in the event of any abnormal pressure occurring in the engine 30 cylinder, due to high compression or to an accumulation of condensation water therein, the same will be relieved by reason of said pressure causing the valve to be lowered from its seat against the pressure provided by the air. Of course, whenever the operator desires arbitrarily 35 to open the cylinder cocks, this is done in the customary manner by relieving the pressure of the air supplied to the under side of the piston.
- It will be noted that, by reason of the provision of the annulus 17 extending upwardly from the guide member 15, it will not be possible for any of the condensation water, or any contaminating material carried thereby, to pass downwardly along the surface of the valve stem 14 40 into the piston chamber 16.
- It will also be noted that, in the normal operation of the device, there will be little likelihood of leakage of the air for controlling the valve, by reason of the peculiar construction of the piston, as well as that of the bonnet 36, which merely has to be reversed in order to lock the valve in the closed position for emergency purposes.
- I claim:
1. A cylinder cock comprising a casing, a guide member mounted therein forming a horizontal partition separating the interior of the casing into a valve chamber and a piston chamber, the casing having a port forming a communication between the engine cylinder and the valve chamber and an opening in the side wall forming a communication between the valve chamber and the exterior, a valve disposed in the valve chamber adapted to close said port, said valve having a stem extending through the guide member, the guide member having an upwardly extending annulus surrounding the valve stem, and the valve member having a recess into which said annulus projects, a piston mounted on the lower end of the valve stem, the casing having a fluid pressure connection and a port extending therefrom to the piston chamber below the piston, a bonnet for closing the lower end of the casing, said bonnet having a boss normally disposed exteriorly but 55

adapted when the bonnet is reversed to hold the valve in the closed position.

2. A cylinder cock comprising a casing, a guide member mounted therein forming a horizontal partition separating the interior of the casing into a valve chamber and a piston chamber, the casing having a port forming a communication between the engine cylinder and the valve chamber and an opening in the side wall forming a communication between the valve chamber and the exterior, a valve disposed in the valve chamber adapted to close said port, said valve having a stem extending through the guide member, the guide member having an upwardly extending annulus surrounding the valve stem, and the valve member having a recess into which said annulus projects, a piston mounted on the lower end of the valve stem, the casing having a fluid pressure connection and a port extending therefrom to the piston chamber below the piston, a bonnet for closing the lower end of the casing, said bonnet having a recess on one side to provide a clearance for the lower end of the valve stem when the valve is in the open position, and the other side of the bonnet having a boss adapted when the bonnet is reversed to hold the valve in the closed position.
3. A cylinder cock comprising a casing, a fluid pressure actuated valve, and a reversible bonnet mounted at the lower end of the casing for closing the same, said bonnet having a boss normally disposed exteriorly but adapted when the bonnet is reversed to hold the valve in the closed position.
4. A cylinder cock comprising a casing having a valve chamber and a port forming a communication between the engine cylinder and said valve chamber, a fluid pressure actuated valve disposed in said valve chamber and adapted to close said port said valve having a downwardly extending stem, the casing also having an opening forming a communication between the valve chamber and the exterior, a reversible bonnet mounted at the lower end of the casing for closing the same, said bonnet having a boss normally disposed exteriorly but adapted when the bonnet is reversed to contact with the lower end of the valve stem thereby to hold the valve in the closed position.
5. A cylinder cock comprising a casing having a valve chamber and a port froming a communication between the engine cylinder and said valve chamber, a fluid pressure actuated valve disposed in said valve chamber and adapted to close said port, said valve having a downwardly extending stem, the casing also having an opening forming a communication between the valve chamber and the exterior, a reversible bonnet mounted at the lower end of the casing for closing the same, said bonnet having a recess on one side to provide a clearance for the lower end of the valve stem when the valve is in the open position, and the other side of the bonnet having a boss adapted when the bonnet is reversed to hold the valve in the closed position.
6. A cylinder cock comprising a casing, a fluid pressure actuated valve, a valve stem for said valve, and a reversible bonnet mounted at the lower end of the casing for closing the same, said bonnet having a projecting portion normally disposed exteriorly but adapted when the bonnet is reversed to contact said valve stem and hold the valve in the closed position.
7. A cylinder cock having a casing, a fluid pressure actuated valve therein, said valve having a downwardly extending stem, and a reversible cover plate mounted at the lower end of the casing for closing the same, said cover plate having a face normally disposed interiorly to provide a clearance for said valve stem and having a projecting portion normally disposed exteriorly but adapted when the cover plate is reversed to hold the valve in the closed position.
8. A cylinder cock comprising a casing having a valve chamber and a port forming a communication between the engine cylinder and said valve chamber, a fluid pressure actuated valve disposed in said valve chamber and adapted in its uppermost position to close said port, said valve having a downwardly extending stem, the casing also having an opening forming a communication between the valve chamber and the exterior, a reversible bonnet mounted at the lower end of the casing for closing the same, said bonnet having a recess on one side to provide a clearance for the lower end of the valve stem when the valve is in the open position, and the other side of the bonnet having a boss adapted when the bonnet is reversed to contact the lower end of said valve stem and hold said valve in the closed position.

ROBERT H. GEORGE. 50
